(57) **CLAIM**

The ornamental design for a surge protector, as shown and described.

DESCRIPTION

FIG. 1 is a front elevation view of a surge protector showing my new design;

FIG. 2 is a rear elevation view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom, front, right side perspective view thereof; and,

FIG. 8 is a top, front, right side perspective view thereof. The broken lines in the figures depict portions of the surge protector that form no part of the claimed design.
